SAFETY CORE INSULATOR

Arthur O. Austin, near Barberton, Ohio

Application June 18, 1936, Serial No. 85,948

4 Claims. (Cl. 174—30)

In the transmission of power and in the insulation of radio stations there is need for insulators of high strength and mechanical reliability, and having good electrical properties. Desirable mechanical and electrical properties may be obtained by making up an insulator having an outer sleeve such as glass or porcelain which will withstand leakage current and weathering but which may carry little or no mechanical load. 5 together with an internal member which sustains the mechanical load particularly where this load is in tension. Insulators of this general type heretofore have been used but they are large and costly, consequently their use is restricted. 10 The previous methods of gripping the internal tension member require rather large and costly heads.

One of the objects of my invention is to provide an improved type of construction which simplifies 20 the mechanical construction and reduces the size, weight and cost of the insulator.

Another object is to provide a construction which will have improved mechanical reliability.

Another object is to provide an improved tension member and method of attaching same.

Other objects and advantages will appear from the following specification and will readily suggest themselves to those skilled in the art.

The invention is exemplified by the combination 30 and arrangement of parts shown in the accompanying drawings and described in the following specification and it is more particularly pointed out in the appended claims.

In the drawings:

35 Figs. 1, 4, 7, 8, 11, and 20 are longitudinal sections of insulators showing different embodiments of the present invention.

Figs. 2, 5, 9, 12, and 21 are transverse sections on lines 2—2, 5—5, 9—9, 12—12, and 21—21, 40 of Figs. 1, 4, 8, 11, and 20 respectively.

Fig. 3 is a fragmentary longitudinal section at right angles to the section shown in Fig. 1.

Fig. 6 is a transverse section on line 5—5 of Fig. 4 but showing the addition of a filler.

45 Fig. 10 is a side elevation of apparatus for forming reinforcing links.

Figs. 13, 15, 17, and 19 are elevations, partly in section showing other forms of the invention.

Fig. 14 is a plan view of Fig. 13.

50 Figs. 16 and 23 are elevations, respectively, of other forms of the invention.

Fig. 18 is a transverse section on line 18—18 of Fig. 17.

55 Fig. 22 is a transverse section, similar to Fig. 21, of a modification of the invention.

Fig. 24 is a transverse section of the member 128 on line 24—24 in Fig. 23.

Fig. 25 is a transverse section of the member 129 on line 25—25 in Fig. 23.

Fig. 26 is a transverse section, similar to Figs. 5 24 and 25, of a modification of member 129 in Fig. 23.

In the form of the invention shown in Figs. 1, 2 and 3 the outer jacket 10 is held between heads 11 having attaching ears 12. Gaskets 13 are provided so that oil or other insulating medium can be retained within the sleeve or member 10 so as to prevent electrical discharge under operating conditions. An insulating link 14 is made in the form of a flat loop. Flat shaped eyes 15 are inserted in a slot 16, and a bearing yoke or keeper 17 is inserted in the eye 15. The yoke has projecting lugs 18 which engage the edges of the link 14. The inner surface of the link bears upon the rounded edge 19 of the member 17, which is shown in section in Fig. 3. The eye members 15 are enlarged at their inner ends as shown at 20 in order to provide increased bearing area between the member 15 and the yoke member 17. The slots 16 are made long enough so 25 that the member 15 with the enlarged portion can be shoved thru the slot. If desired two separate links can be used although the single unit is preferable as it tends to prevent disengaging of the parts. The space between the internal elements and the sleeve is filled with oil or insulating compound, sufficient space being allowed only for the expansion of the material unless separate expansion chambers are provided.

In Fig. 1 the heads 11 are screwed onto the 35 studs 21. This places the sleeve 10 in compression and the insulating link 14 in tension. In general sufficient tension is applied on the central member so that under working conditions the seal between the insulating sleeve 10 and the 40 heads 11 will not be broken. In other words the insulators are preloaded. This has some very great advantages as cement joints and packing glands are eliminated. This greatly reduces the size and cost of the insulator and tends to eliminate mechanical stress which may cause damage to the insulating sleeve 10, brought about by the large difference in the linear coefficient of expansion between the insulating sleeve 10 and the metal for changes in temperature. Due to 45 the practical elimination of this so-called thermal stress, materials such as copper, bronze or aluminum which have higher linear coefficients of expansion than iron or steel can be used without increasing the danger of cracking of the insulat- 55

ing member, which usually is porcelain or glass having a relatively low linear coefficient of expansion.

In Fig. 1 a construction is used which permits of the use of an insulating link having a cross section which is a large percentage of the cross section of the opening in the insulating sleeve. Insulating sleeves are not necessarily restricted to circular types, but these are the most easily constructed and generally are stronger mechanically than members having rectangular cross sections. Where the cross section of the insulating link constitutes a large percentage of the cross section of the opening in the insulating sleeve, the size and cost of the latter can be materially decreased.

Where the space 22 between the insulating link and the insulating sleeve is relatively small, the volume of oil or insulating compound is reduced. Since most insulating compounds have a relatively large volumetric coefficient of expansion for changes in temperature, this small volume has the advantage that reduced space can be provided for the expansion of the filling medium for the higher temperatures. Where this volume is small expansion chambers may be omitted or the length of the insulating links with respect to the sleeve may be increased. Where appreciable space is required particularly for long insulators the insulating links may not be covered by the insulating medium. When working at high voltages this may subject the insulating link to electrical discharges. In order to prevent this shields 23 which are electrically connected to the terminals thru the draw bolts 15 and yokes 17 are provided. Other forms of shielding may be used which will permit a lowered level of the filling medium without exposing the insulating links to a discharge.

Where it is not necessary to use as large a cross section of the link as the interior of the insulating member will permit, other types of construction may be used. A construction of this kind is shown in Fig. 4.

In Fig. 4 the insulating link 24 has a much smaller cross section relative to the opening in the sleeve 25 than in Fig. 1. A cross section thru the center of the insulator is shown in Fig. 5. The space 26 between the insulating link 24 and the insulating sleeve 25 is relatively large. In Fig. 4 one end of the insulating link 24 is held by a U shaped bolt 27. The other end is held by a pin 28 which passes thru ears 29 which are a part of the head 30. The reaction between the insulating link 24 and the insulating sleeve 25 is obtained by tightening the nuts 31 which bear upon the head 32. Load is applied to the insulator by means of the eye 33 and clevis 34.

Where it is desired to reduce the volume of the insulating medium used to fill the space between the insulating link and the sleeve, this may be accomplished by suitable insulating fillers. One method of construction is shown in Fig. 6. In Fig. 6 sectional pieces of insulation 35 and 36 are placed in the slot formed by the two sides of the link 24. By making the pieces with suitable interlocking projections they will be held in place while the link mechanism is passed thru the insulating sleeve 25. It is readily seen that these filling members will displace a large portion of the filling liquid in the space between the insulating links and the insulating tube. The amount of filling medium may be further reduced by filling in any remaining space 37 with sand or insulating material. By using methods of this kind the amount of filling medium may be greatly reduced so that the space required for

expansion will be exceedingly small. This is important where an expensive filling material is used or where the insulator is operating in a horizontal or nearly horizontal position and it is desired to eliminate a space which may permit of a discharge inside the tube when the insulator is subjected to a high voltage or to lightning.

This method of reducing the volume of filling material is applicable to practically all of the various types of insulators shown in the several figures. In some cases the filling pieces and material can be used to prevent internal discharge and increase the internal breakdown voltage. This is valuable where the length of the insulating sleeve is so short that the links which engage the insulating member are brought near together.

Fig. 7 shows a further modification of the insulator shown in Fig. 1. The method of gripping the insulating link is the same. However, the insulating sleeve 38 bears against a terminal 39 at one end and expansion chamber 40 at the other. The expansion chamber allows for variations in volume of the filling medium. The construction has the advantage that the initial or preloading of the insulator can be applied very easily and determined with a high degree of accuracy. The insulating link 41 with the tension eye 42 is passed thru the insulating sleeve 38 and the expansion chamber 40. Ground joints 43 may be coated to insure a tight seal between the insulating sleeve and the adjacent terminal members when they are under pressure. If desired gaskets may be applied at this point. The draw eye 42 is provided with a long threaded stud 44 and a nut 45. By using a suitable mechanism which will draw the stud 44 outward thru the top of the expansion chamber 40 it is possible to subject the link 41 to tension and set up the desired pressure between the insulating sleeve 38 and the terminals at the joint 43. It is evident that this may be readily accomplished by attaching suitable pulling means to the end of the stud 44 and applying an equivalent pressure against the top of the expansion chamber 40, the eye member 46 being removed. When the necessary stress is set up the nut 45 may be seated against the top of the expansion chamber. This nut can be used to form a tight seal. The resiliency or deformation in the various mechanical parts will maintain the pressure under operating conditions.

After the insulator is assembled the eye member 46 may be screwed onto the stud 44. A filling plug 47 is provided so that the insulating medium 48 may be poured into the insulator. The expansion chamber is provided with a weather shed or shield 49 which deflects drip water and reduces the leakage loss of the insulator under storm conditions. This member also provides an electrostatic shield.

In Fig. 7 the insulator is suitable where it is operating in a vertical or inclined position. Where the insulator is operating in a horizontal position it generally is advisable to place the expansion chamber above the insulator. An arrangement of this kind is shown in Fig. 8. The expansion chamber 50 is provided with an opening 51 which connects with the interior of the insulator. Since the expansion chamber is well above the insulating sleeve 52, the space between the insulating links 53 and 54 and the insulating sleeve can be maintained full of the insulating medium at all times. The general method of preloading the insulator which was described in Fig. 7 can be applied to the insulator shown in Fig. 8.

Fig. 8. However, the tension member 55 is in the form of a clevis having ears 56. A pin 57 passes thru the ears 56 and engages the insulating links 53 and 54. Tension is applied to the draw clevis 55 before the terminal eye 58 is screwed in place, after which the nut 59 may be tightened and the terminal bolt 58 screwed into position. A filling plug 60 is provided for the expansion chamber.

Where high strengths are desired a single insulating link may become quite thick and difficult to form and cure. If desired the tension member may be made up of two links 53 and 54. A cross section thru the insulating sleeve 52 and the links 53 and 54 is shown in Fig. 9. The link 54 is made so that it can be slipped over the link 53. The links are held at one end by a pin 61 which is elongated in cross section. This pin bears against the terminal head 62 and is sealed in by a plug 63. The elongated or oval shape of the pin 61 provides stiffness even though the space between the sides of the insulating link 53 is relatively small.

In order to provide an efficient insulator the insulating link must be of small size and have high strength for a given cross section, and must be easily formed. In order to provide an efficient tension member a design of insulating link has been developed which will meet the various conditions very satisfactorily. Insulating links embodying the above advantages can be made up in several different ways. A very satisfactory link is one made of canvas or fabric treated with a phenolic condensation product well known in the art by the trade name "Bakelite". The style of link used has the advantage that links of various lengths can be readily made without being limited as to the width of the fabric. In order to form the links treated fabric of any desired width is wound over flat mandrels while being subject to heat and tension. After the mandrels are covered to the desired thickness they are placed in a vulcanizing or treating press where they are cured.

Such an arrangement is shown in Fig. 10 in which the fabric 64 to be treated is wound on a mandrel 65. The mandrel is provided with pins 66 which engage driving mechanism so that the fabric can be wound onto the mandrel under tension. If desired the mandrel may be made in parts with joints at 67 so that various lengths of links can be made by simply using the different lengths of mandrel between the carefully formed ends. The mandrel 68 is equipped with separable ends 69 and springs 70 which place the fabric under tension while being treated. The platens 71, 72 and 73 are heated and the rams 74 subject the fabric to pressure while curing. This insures a dense material and binds the various fibers together.

An increased strength is obtained by using fabric which has the strongest threads running lengthwise. This method of forming links makes it possible to use good widths of material to form a wide link. After treating narrow links may be sawed or cut from the wide link. This greatly reduces the cost of producing a link and makes it possible to obtain a wide range in the size and strength with a minimum amount of equipment. It is evident that a suitable mandrel may be wrapped with a treated cord. Individual links may be formed by using platens with suitable grooves or by placing forms between the platens. This method makes it possible to conform more nearly to the shape of the inner

surface of the tube. The cord has to be wound under considerable tension in order to provide a compact mass which will distribute the load between the various cords.

In Fig. 11 a somewhat different form is shown. The insulating sleeve is composed of two members 75 and 76. Two rain sheds or shields 77 and 78 also are used. The tension member is composed of an inner insulating link 79 and an outer insulating link 80. The inner insulating link bears 10 upon pins 81 and 82, and the outer insulating link bears upon pins 83 and 84. Using separate bearing members for the two links reduces the maximum bearing pressure between the pins and fabric, and permits of a larger cross section in the 15 tension members without a reduction in the ultimate strength for a given cross section. The lower head 85 is provided with ears, the construction being similar to that in Fig. 4. The insulator is given an initial load in the same manner as 20 that of Fig. 7 and Fig. 8. The nut 86 bears upon a recess in the weather shed 77. After the insulator is given the desired loading the clevis or eye 87 is screwed into position. By placing some initial pressure between the heads and the 25 insulating sleeves it is possible to fill the insulators to the desired point before placing them under final tension. In this way any special filling means can be omitted as the insulator can be filled thru the space between the draw bolt 30 and the cap 77 before the nut 86 is tightened. If desired filling and draining means may be readily applied. In this type of construction additional weather sheds may be used which will greatly reduce the leakage loss during rains. The 35 weather sheds also can be used to set up a more uniform gradient, as they act as capacitance plates. For very high working loads the weather sheds preferably are of metal. Where the insulating housing or sleeves are not subject to 40 heavy working stresses the weather sheds like that shown in 78 can be formed of insulation, thereby adding to the surface insulation of the insulator. Where insulating flanges or weather sheds are used they usually have much greater 45 thickness at the point where they are clamped between the adjacent insulating sleeves. This is in order to prevent a discharge over the inner surface due to the voltage built up over the outside.

Fig. 13 shows a different modification in which the insulating link 88 is surrounded by an insulating member 89 which is provided with petticoats or weather sheds 90. The space 91 may be partially filled with insulating oil or compound 55 as previously described. The insulator is provided with a wire groove 92 and holes 93 for attaching a clamp which will hold the conductor in the groove 92. The insulator is given a conical shape so as to provide high strength for side 60 pull where the insulator is rigidly mounted by the base 94.

Fig. 14 is a plan looking down on the top of the insulator, and shows the holes 95 for bolting the base 94. The draw link is similar to 27 in Fig. 4. 65 Tension is applied by tightening the nuts 96. The plug 97 is provided so that the insulator may be filled with insulating oil or compound. The use of an insulating link which is easily and cheaply made and which may be gripped with interlinked 70 attachments makes it possible to construct a number of different insulators on a more efficient basis than heretofore.

In Fig. 15 the insulating link 98 is attached to terminal members using some one of the vari- 75

ous schemes described. Insulating members 99, 100 and 101 are clamped between the terminal members 102 and 103. Gaskets or joints are provided between the various sections, or the housing may be made in one piece if desired. In order to prevent internal discharge where the oil level does not entirely cover the insulating member a pocket 104 lined with a conducting coating may be used to screen the insulating member 98.

10 In Fig. 16 the general construction is similar to that of Fig. 13 with the exception that the insulator is provided with ears 105 which are attached to a bracket 106 by a bolt or pin 107. This arrangement allows the insulator to swing 15 in the direction of the line, relieving it of a large portion if not all of the bending moment due to a broken conductor or an unbalanced stress in the conductor 108. At the same time the construction provides rigidity so as to prevent side 20 sway of the conductors under transverse wind loads. This type of construction is particularly applicable to railway work.

Fig. 17 shows an application of the insulating link in the construction of multiple element post 25 or radio insulators. In this construction insulating members 109 and 110 are gripped between plates 111, 112 and 113. A cross section between plates 111 and 112 is shown in Fig. 18. The several plates are provided with suitable bearing surfaces and gaskets. Draw clevises or attachments 114 and 115 are provided so that insulating links 116 can be placed under tension. This clamps the plates and insulating members together, forming sealed in compartments or 30 spaces for the insulating links 116. This method of construction has the advantage that several insulating members may be used in multiple to provide a high mechanical strength in tension, compression or for bending moment. By reducing 35 the length of the individual insulating members and using intermediate moment plates or members such as 112 the strength of the insulator for a transverse load applied at the top is greatly increased. The insulators may be heated 40 with a heating element immersed in the filling liquid, or by an outside circulating system. Ports 117 and 118 provide for a circulation of the oil. An additional expansion chamber may be provided 45 as in some of the other types so that the space within the insulating sleeves will be completely filled and a circulation of warm oil can be obtained. The circulation of the oil is desirable as it is then possible to warm the surface of the insulator to removed films of moisture.

Fig. 19 shows another application of the insulating link. This is similar to Fig. 15 with the exception that the insulating housing 119 is made in a single piece.

50 In Fig. 20 the conical insulating housing 120 provides rigidity for a post or pillar insulator, where the conductor is mounted above the insulator in the wire groove 121. The insulator is provided with a metal rain shed or shield 122 which projects well down into the open end of the insulating member 120. The insulating link 123 is attached inside this projection by a suitable pin 124. The downwardly projecting portion 125 of the member 122 engages an insulating member 126. The object of the insulating member 126 is to provide rigidity for the insulator in case that the insulating sleeve 120 is damaged. As the member 120 usually is made of fragile material this member may be damaged by shooting or by rocks thrown against the insulator. It

is highly desirable that the insulating member will not drop the conductor, which may be carrying a high voltage. The member 126 has sufficient strength so that the conductor can be sustained where the fragile insulating sleeve is 5 damaged. In the case of pendant or underhung insulators an additional sleeve is not necessary as the links are in tension and not subject to bending moment. The intervening space is filled with oil, just sufficient space being allowed for 10 expansion.

The various types of the insulators shown are particularly applicable where it is desirable to prevent discharges which will cause radio interference, the electrostatic field due to the construction being very favorable to operation at high voltage. The insulators have small electrostatic capacity and therefore they are particularly valuable for installation in fog districts, for radio strain insulators and for insulating 15 self-supporting radiators.

Fig. 21 is a section thru Fig. 20 showing the safety sleeve 126.

Other arrangements may be used such as that shown in Fig. 22 in which the insulating link is 25 surrounded by a safety member 127 composed of wood or other suitable material.

Fig. 23 shows an application of an insulating cross arm of the swinging type. The member 128 is a tension member, and the member 129 30 normally is in compression but may be thrown in tension. This member being in approximately horizontal position is provided with an expansion chamber 130. The arms support an insulator string 131. The member 129 may be constructed 35 in several different ways with or without safety compression members.

Fig. 25 shows one construction in which a non-shattering insulating sleeve 132 is placed between the insulating link 133 and the fragile insulating member 134.

Fig. 26 shows a section with a different form of safety compression member 135 formed of wood or other material. Grooves 136 may be placed in the side into which the tension insulating links 45 can be fitted.

I claim:

1. An insulator comprising a housing of solid insulating material, fittings at each end of said housing, a tension member in the form of a 50 closed loop of insulating material connecting said fittings, solid insulating filling within said housing and extending between the arms of said loop in space not occupied by said arms, and a filling liquid or compound filling remaining space within 55 said housing.

2. An insulator comprising a link of insulating materials, the arms of the link being flat bars extending close together and disposed side by side providing a slot therebetween and extending 60 about the ends of the link to form loops connecting the two arms, and fittings for opposite ends for said link, said fittings comprising keepers extending through the slot between said arms and engaging said loops, and attachment means 65 secured to said keepers for applying a load to said insulator, said link being formed of fibrous material impregnated with an artificial resin and cured to impart rigidity to said links.

3. An insulator comprising a link of insulating 70 materials, the arms of the link being flat bars extending close together and disposed side by side providing a slot therebetween and extending about the ends of the link to form loops connecting the two arms, and fittings for opposite ends 75

for said link, said fittings comprising keepers extending through the slot between said arms and engaging said loops, and attachment means secured to said keepers for applying a load to said insulator, said link being formed of fibrous material impregnated with an artificial resin and cured to impart rigidity to said link, and a housing member of rigid dielectric material enclosing said link.

10 4. An insulator comprising a tubular housing member of rigid dielectric material, fittings bearing against the opposite ends of said tubular

member and a link of non-fragile dielectric material connecting said fittings, said link comprising a continuous flat bar formed into a loop, the opposite ends of said loop being disposed adjacent said fittings, keepers passing through said loop, one at each end thereof, said bar being slotted transversely of said keepers, and eye members projecting from said fittings and extending into the slots in said bar to engage said keepers and connect said loop with said fittings. 5

10

ARTHUR O. AUSTIN.
